SLUG CASTING MACHINE

Artemas B. Watson, Columbia, S. C., assignor to
Mergenthaler Linotype Company, a corporation
of New York

Application July 30, 1938, Serial No. 222,159

12 Claims. (Cl. 199—53)

This invention relates to typographical slug casting machines of the general organization represented in U. S. Letters Patent to O. Mergenthaler wherein a composed line of matrices is presented to the front face of a slotted mold, the mouthpiece of a metal pot presented against the rear face of the mold, and molten metal injected by a pump from the metal pot into the mold slot or cavity to form a type-bar or slug.

10 In such machines the various operations, such as the presentation of the mouthpiece of the metal pot against the rear face of the mold and the working of the pump, are controlled by a number of cams fast to a main drive shaft driven by a clutch which is adapted to be engaged and disengaged by the operation of a fore-and-aft rod. (both manually and automatically controlled).

15 The metal pot is pivotally mounted in the machine and, just prior to the casting operation, the mouthpiece thereof is brought into engagement with the rear face of the mold by rocking or tilting the pot forward under the influence of one of the cams which engages with a roller of a vertically disposed lever carried by the metal pot. To insure metal tight engagement between the mouthpiece and the face of the mold, as well as to prevent damage to the machine in the event the rocking or forward movement of the pot is arrested before the mouthpiece is presented against the face of the mold, the lever is resiliently mounted, that is to say, the upper end of the lever is pivotally secured to the pot and the lower end thereof is adapted to move forwardly 20 toward the pot under the influence of the rotating cam against the action of a spring when the forward movement of the pot is arrested, the extent of this movement being determined by the distance that the metal pot is arrested back of its most forward or normal casting position.

25 The pump which is operated to inject a charge of molten metal from the pot into the mold slot or cavity is operated by another of the cams on the main drive shaft, and since the main drive shaft normally makes one complete revolution before it is automatically brought to rest at the end of a machine cycle of operation by the disengagement of the clutch, the pump operates even though the advance of the pot is arrested before the mouthpiece is presented against the face of the mold. Under such conditions, a bad metal "squirt" is bound to result.

30 The present invention is intended to overcome the above and other objections and contemplates automatic means for stopping the machine when-

ever the advance of the metal pot is arrested before the mouthpiece thereof is presented against the face of the mold. Specifically, the machine is provided with a rocker arm having one of its ends so positioned that the lower end of the pot lever comes to rest immediately behind it as the pot is arrested when the mouthpiece is presented against the rear face of the mold. The other end of the rocker arm is positioned in front of a stud carried by the fore-and-aft rod by which the clutch is engaged and disengaged. By this arrangement, when the advance of the metal pot is arrested before the mouthpiece is presented against the face of the mold and the lower end of the resilient lever moves forwardly a correspondingly greater distance than normally, the rocker arm is rotated and, in doing so, engages the stud carried by the fore-and-aft rod and forces the latter backwardly to disengage the clutch and stop the machine before the pump is permitted to 20 operate.

35 For a clear understanding of the present invention, reference may be made to the accompanying drawings wherein it is shown in preferred form and by way of example. It will be 25 obvious, however, that many changes and alterations may be made therein and in its mode of adaptation without departing from its spirit, and it is to be understood that the invention is not limited to any specific form or embodiment except insofar as such limitations are specified in the appended claims.

40 Referring to the drawings:

Fig. 1 is a side elevation, partly in section, of the casting mechanism constructed in accordance 35 with the present invention;

Fig. 2 is an elevation of the main driving clutch and the mechanism employed in rendering it inoperative in the event the mouthpiece of the metal pot is not brought into engagement with the rear face of the mold; and

Fig. 3 is a view taken along the line 3—3 of Fig. 1.

45 In the drawings, 10 represents a metal pot in which molten metal is stored. As usual, the pot 10 is provided with a well or cylinder 11 from which a throat 12 leads upwardly and outwardly to a mouthpiece 13. The pot 10 is arranged to be rocked or tilted forwardly and backwardly to carry the mouthpiece 13 into and out of engagement with the rear face of a slotted mold 14 carried by a rotary disc 15. To this end, the pot 10 is provided with a pair of front supporting legs 16 (only one being shown) mounted to turn on a rod 17 supported in the frame of the machine. 50 55

At the rear, the pot 10 is provided with a pair of brackets 18 (only one being shown) in which is pivotally mounted, by a pin 19, the upper end of a lever 20 whose central portion is provided with a roller 21 adapted to track upon the periphery of a cam 22 fast to the main shaft 23 of the machine. The lower end of the lever 20 is resiliently connected to the pot 10, being provided with an aperture through which extends the free end of a short rod 24, whose other end is pivoted to a bracket 25 depending from the bottom of the metal pot. A compression spring 26, positioned about the rod and confined between two collars 27 and 28 respectively, maintains the lower end of the lever 20 resiliently away from the pot 10, the distance being governed by means of a pair of adjusting nuts 29 threaded onto the free end of the rod 24.

The peripheral face of the pot operating cam 22, as usual, is concentric throughout, except for one portion where it is raised to provide an operating segment 30. When the roller 21 is in contact with the lower portion of the cam 22, the pot 10 is in its rearward or inoperative position, and this condition obtains until just before the casting operation, when the cam 22 rotating in the direction indicated, brings the raised portion 30 into engagement with the roller 21, thus rocking or tilting the pot 10 forwardly through the medium of the resilient lever 20 until the face of the mouthpiece 13 engages the rear face of the mold 14 at which time the lower end of the lever 20 moves forwardly a slight distance against the action of the spring 26. As the cam 22 continues to rotate, the roller 21 runs back onto the lower portion and thus permits the pot 10, under its own weight, to rock rearwardly to its inoperative position to await the next casting operation.

As usual, a plunger 31 is positioned in the well 40 or cylinder 11 of the metal pot 10, and it is connected by means of a rod or link 32 to the long arm of a bell crank lever 33 having a sleeve portion 34 journaled on a fixed transverse rod 35 of the machine frame and provided with an arm 36 extending laterally beneath a second lever 37 which is also journaled on the rod 35 and connected at its free end to a pull spring 38. This spring is anchored to the main frame of the machine and actuates the plunger 31 through the connections just described. The shorter arm of the bell crank 33 is provided with a roller 39 arranged to track upon the periphery of the usual rotary cam 40 fast to the main shaft of the machine. The peripheral face of the cam 40 is concentric throughout, except at one portion of its circumference where it is cut away or formed with a depression 41. When the machine is at rest, the roller 39 is in contact with the concentric portion of the cam, so that the plunger 31 is maintained in its raised or inoperative position. This condition obtains, until after the mouthpiece 13 of the metal pot 10 has been pressed into engagement with the rear face of the mold 14, when the cam 40 rotating in the direction indicated brings the downwardly sloping surface of the depression 41 into engagement with the roller 31, which then quickly descends along such surface toward the bottom of the depression, thus permitting the spring 38 to depress the plunger 31 and force a charge of molten metal into the slotted mold 14 to form a type-bar or slug against a composed line of matrices 42 which previously had been presented against the front face of the mold in the manner well understood in the art.

As the cam 40 continues to rotate, the roller 39

is subsequently engaged by the upwardly sloping surface of the depression 41 and the plunger 31 thereby restored to its normal raised position to await the next casting operation.

The main shaft 23 of the machine on which the cams are mounted, is driven by power operated means including a large gear wheel 43 meshing with a driving pinion 44 on an auxiliary shaft 45 which is equipped with the customary main driving clutch (see Rogers Patent No. 661,386), comprising a pulley 46 and clutch shoes 47. The operation of the clutch shoes 47 to render the clutch operative and inoperative is effected, as usual, by a fore-and-aft rod 48 which when moved forwardly engages the clutch to inaugurate a machine cycle of operation and when moved backwardly disengages the clutch to stop the machine.

In accordance with the present invention, means are provided for moving the fore-and-aft rod 48 backwardly to stop the machine automatically before the plunger 31 operates in the event that the forward movement of the metal pot 10 is arrested and the mouthpiece 13 is not pressed into engagement with the rear face of the mold 14.

To this end, the usual pot lever 20 is replaced with one of greater length having an offset lower end 49. On a bracket 50 secured to the machine frame, a rocker arm 51 is rotatably mounted by means of a stud 52. One end of the rocker arm 51 is provided with an adjusting screw 53 which is so positioned that the lower end 49 of the lever comes to rest immediately behind it when the metal pot is rocked forwardly to present the mouthpiece 13 against the rear face of the mold 14. The other end of the rocker arm 51 is so positioned as to be immediately in front of a stud 54 carried by the fore-and-aft rod 48 when the rod is in its forward or clutch operating position. Under these conditions, when the advance of the metal pot 10 is arrested before the mouthpiece 13 is presented against the face of the mold 14, the lower end 49 of the lever 20 moves forwardly against the action of the spring 26 a much greater distance than it normally does, and as it so moves forwardly, it engages the adjusting screw 53 and thus rotates the rocker arm 51. As the rocker arm 51 rotates, it engages the stud 54 and forces the fore-and-aft rod 48 backwardly to disengage the clutch and stop the machine.

By referring to Fig. 1, it is seen that the depressed portion 41 does not come into action to operate the plunger 31 until some time after the raised portion 30 of the pot operating cam 22 has rocked the pot 10 forwardly to present the mouthpiece 13 against the rear face of the mold 14. Consequently, when the advance of the pot 10 is arrested before the mouthpiece 13 is presented against the face of the mold 14, the clutch is automatically disengaged to stop the machine before the plunger 31 is permitted to operate to inject a charge of molten metal from the pot 10.

After the machine has been stopped and the cause remedied, the fore-and-aft rod 48 may be pulled forwardly to start the machine, the pin 55 engaging the rocker arm 51 and restoring it to its operative position.

Having thus described my invention, what I claim is:

1. In or for a slug casting machine, the combination of a slotted mold, a metal pot having a mouthpiece, power operated means for advancing the metal pot to present the mouthpiece against one face of said mold, and safety means inter-

posed between the power operated means and the metal pot for rendering the power operated means inoperative when the advance of the metal pot is arrested before the mouthpiece is presented against the face of said mold.

5. 2. In or for a slug casting machine, the combination of a slotted mold, a metal pot having a mouthpiece, power operated means for advancing the metal pot to present the mouthpiece against one face of said mold, a pump for forcibly injecting molten metal from said pot through said mouthpiece into said mold, and safety means interposed between the power operated means and the metal pot for rendering the power operated means inoperative before the pump is permitted to operate when the advance of the metal pot is arrested before the mouthpiece is presented against the face of said mold.

3. In or for a slug casting machine, the combination of a slotted mold, a metal pot having a mouthpiece, a main drive shaft, a clutch for driving said shaft, a cam fast to said shaft, means responsive to the rotation of said cam for advancing said pot to present the mouthpiece against one face of said mold, and safety means interposed between the cam and the metal pot for disengaging said clutch when the advance of said pot is arrested before the mouthpiece is presented against the face of the mold.

30. 4. In or for a slug casting machine, the combination of a slotted mold, a metal pot having a mouthpiece, a main drive shaft, a clutch for driving said shaft, a cam fast to said shaft, resilient means interposed between said cam and said pot for advancing the pot to present the mouthpiece against one face of the mold in response to the rotation of said cam, and means actuated by said resilient means for disengaging the clutch when the advance of the pot is arrested before the mouthpiece is presented against the face of the mold.

45. 5. In or for a slug casting machine, the combination of a slotted mold, a metal pot having a mouthpiece, a main drive shaft, a clutch for driving said shaft, a cam fast to said shaft, resilient means interposed between said cam and said pot for advancing the pot to present the mouthpiece against one face of the mold in response to the rotation of the cam, and means rendered operative through the yielding of said resilient means for disengaging said clutch when the normal advance of the pot is arrested.

60. 6. In or for a slug casting machine, the combination of a slotted mold, a melting pot having a mouthpiece, a main drive shaft, a clutch for driving said shaft, a cam fast to said shaft, a resiliently mounted lever interposed between said cam and said pot adapted to advance the pot to present the mouthpiece against one face of the mold in response to the rotation of the cam, and means rendered active through the yielding of said lever for disengaging said clutch when the normal advance of the pot is arrested.

65. 7. In or for a slug casting machine, the combination of a slotted mold, a metal pot having a mouthpiece, a main drive shaft, a clutch for driving said shaft, a cam fast to said shaft, a lever interposed between said cam and said pot adapted to advance said pot in response to the rotation of said shaft to present the mouthpiece against one face of said mold and to move abnormally towards said pot when the advance of said pot is arrested, and means responsive to such abnormal movement of said lever towards said pot for disengaging said clutch.

8. In or for a slug casting machine, the combination of a slotted mold, a melting pot having a mouthpiece, a main drive shaft, a clutch for driving said shaft, a cam fast to said shaft, a resilient lever interposed between said cam and said pot adapted to advance the pot in response to the rotation of said cam to present the mouthpiece against one face of the mold and to move abnormally relatively to the pot when the advance of the pot is arrested, and means rendered active by such abnormal movement of said lever for disengaging said clutch.

9. In or for a slug casting machine, the combination of a slotted mold, a melting pot having a mouthpiece, a main drive shaft, a clutch for driving said shaft, a cam fast to said shaft, a lever interposed between said pot and said cam and adapted to advance the metal pot to present the mouthpiece against one face of said mold in response to the rotation of the cam, one end of said lever being pivotally secured to said pot and the other end thereof being so mounted that it moves abnormally towards the pot when the advance of the pot is arrested, and means responsive to such abnormal movement of the lever towards the pot for disengaging the clutch.

10. In or for a slug casting machine, the combination of a slotted mold, a melting pot having a mouthpiece, a main drive shaft, a clutch for driving said shaft, a cam fast to said shaft, a fore-and-aft rod for rendering the clutch operative and inoperative, a lever interposed between the pot and the cam adapted to advance the pot to present the mouthpiece into engagement with one face of said mold in response to the rotation of said cam, one end of said lever being pivotally secured to said pot and the other end of the lever being so mounted that it moves towards said pot when the advance of said pot is arrested, and means responsive to the movement of said lever towards the pot for operating said rod to disengage said clutch when the advance of said pot is arrested before the mouthpiece thereof is presented against the face of said mold.

11. In or for a slug casting machine, the combination of a slotted mold, a melting pot having a mouthpiece, a main drive shaft, a clutch for driving said shaft, a cam fast to said shaft, a fore-and-aft rod for engaging and disengaging said clutch, a lever interposed between the pot and said cam adapted to advance the pot to present the mouthpiece into engagement with one face of said mold in response to the rotation of said cam, one end of said lever being pivotally secured to said pot and the other end of said lever being so mounted that it moves towards the pot when the advance of the pot is arrested, and a rocker arm actuated by the movement of said lever towards the pot for operating said rod to disengage said clutch when the advance of said pot is arrested before the mouthpiece thereof is presented against the face of said mold.

12. In or for a slug casting machine, the combination of a slotted mold, a metal pot having a mouthpiece, a main drive shaft, a cam fast to said shaft and operative to advance said pot to present the mouthpiece against one face of said mold, and automatic means interposed between the cam and the metal pot for arresting the rotation of the main drive shaft when the advance of said pot is arrested before the mouthpiece is presented against the face of the mold.
